UNITED STATES PATENT OFFICE.

JOSHUA MERRILL, OF BOSTON, MASSACHUSETTS.

IMPROVEMENT IN CASKS, BARRELS, &c.

Specification forming part of Letters Patent No. 58,449, dated October 2, 1866.

To all whom it may concern:

Be it known that I, JOSHUA MERRILL, of the city of Boston, in the county of Suffolk and State of Massachusetts, have invented certain new and useful Improvements in Casks, Barrels, and Kegs suitable for holding and transporting liquids; and I do hereby declare that the following is a full and correct description thereof, reference being had to the annexed drawings, and to the letters of reference thereon.

My said invention consists in protecting the joints of ordinary casks, barrels, and kegs suitable for holding and transporting petroleums, alcohol, and similar fluids against leakage by cementing them together with glue or other similar gelatinous cement applied to said joints when the staves and head pieces are separated or before they are put together.

The drawings show a cask cemented by glue at the joints.

Figure 1 is a top view of the cask; Fig. 2, a cross-section; Fig. 3, a vertical section through the heads and staves; Fig. 4, a section of a stave.

In carrying out my invention, I take the staves *a* and head-pieces *d* of the cask after they have been properly made and plain-jointed, and apply hot glue to the joints *b* by dipping or by a brush, and then at once proceed to set them up. If the staves have been properly made and jointed they can be trussed and the heads put in before the glue sets, es-

pecially if the staves and heads are from an old cask, or, if new, are bent and crooked before setting up.

The driving up of the hoops forces the glue into the pores of the joints, imparting great strength to the cask when the glue sets, besides resisting the leakage of petroleums, alcohol, and liquids that do not dissolve glue.

The casks made as above described may be coated inside by a coating of glue or shellac, according to the liquid the cask is designed for. The coating of the inside is well known and not necessary to be described, except to say that it may readily be done with glue by pouring into the cask a few gallons of hot glue solution; and then, by putting in the bung tight and rolling the cask about, the air within, being heated by the hot glue, forces it into the pores of the interior surface of the heads and staves.

I claim—

As of my invention and improvement in casks, barrels, and kegs, in combination with the joints of a cask suitable for holding and transporting liquids, having the common straight or plain joints, a coating or stuffing of glue or similar gelatinous cement applied to the joints before putting the cask together, substantially as described.

JOSHUA MERRILL.
